UNITED STATES PATENT OFFICE.

ERNEST A. STEPHENS, OF ELKHART, INDIANA.

COMPUTING SCALE.

Application filed February 13, 1922. Serial No. 536,142.

To all whom it may concern:

Be it known that I, ERNEST A. STEPHENS, of the city of Elkhart, county of Elkhart, Indiana, and a citizen of the United States, have invented certain new and useful Improvements in Computing Scales, of which the following is a specification.

This invention relates to improvements in computing scales.

- 10 An object of the invention is to enlarge the capacity of the indicating device on computing scales by combining with the ordinary indicating chart a supplementary chart or member having indicating elements arranged in suitable local relation to the indicating elements of the ordinary computing chart and in suitable quantitative relation to the indications of the computing chart.
- 20 Another object of the invention is to combine with the chart of computing scales a manually operable indicating device which is manually adjustable to positions in which its indicating elements of different groups 25 can be brought into suitable relation with the indicating elements of the chart so as to render variable the enlargement of the ordinary computing chart on scales of this character.
- 30 It is furthermore an object of the invention to provide in combination with a movable computing chart for scales of this kind, means for yieldingly retaining the chart in a suitable position so as to avoid displacement after the adjustment of the chart has 35 been effected.

- 40 It is also an object of the invention to provide a device of this kind which can readily be attached to ordinary computing scales without requiring a change in the weighing mechanism or in the indicator mechanism proper, and which attachment can be effected without necessitating a disassembly 45 of the scale mechanism or a rearrangement of important parts of the same.

- 50 The invention has numerous other objects which will become more apparent from a perusal of the following specification, in which a preferred embodiment of the invention is described, the novel features being pointed out in the claims appended to the specification, in which reference is made to the accompanying drawings.

- 55 In the drawings:
- Fig. 1 is a front elevation of a computing scale with the improved indicator device at-

tached thereto, certain parts being shown broken away;

Fig. 2 is a central vertical section, and partly elevation through the carrier for the 60 supplementary chart;

Fig. 3 is a horizontal section on 3—3 of Fig. 2;

Fig. 4 is a horizontal detail section on 4—4 of Fig. 2, and

Fig. 5 shows the arrangement of the indicating data on the supplementary chart.

The computing scale, indicated as a whole at 1, is shown by way of example only as comprising the ordinary casing with a 70 weighing platform, and the weighing mechanism is also indicated as a whole at 2. This weighing mechanism includes the steelyard or beam 3, on which a poise 4 is slidably mounted; the beam being supported in a known way by knife-edge fulcrums and being provided at one end with an attachment 5 for the suspension of removable counterweights through which the capacity of the scale may be enlarged in a known 75 way.

The indicating device of the scale is supported by an extension 6 on the scale housing, and includes a substantially fan-shaped chart 7 over which an indicator or pointer 8 plays, the position of the pointer being dependent upon the load which rests on the platform.

The chart 7 comprises an arcuate top row of weight indicating elements 9, showing 85 units and fractions of units. In the embodiment illustrated in the drawing (Fig. 1) the capacity of the indicating device is limited to ten pounds. In addition to these weight indications 9 which are arranged in 90 the top row of the indicating chart, the latter also displays a relatively large number of similar concentric arcuate rows 10. These arcuate rows 10 of indications contain the indications of total prices of commodities, and the indications themselves are arranged in groups 11 radially disposed with respect to the arcs 10. A few of the indications only are entered by way of example in the drawings. The values of these 95 indications increase from the lowermost row 10 upwardly in accordance with unit price indications 12, which are applied to the pointer. If, for instance, the pointer indicates (in the top row 9) a weight of a commodity of seven pounds and if the unit price per pound (indication 12 on the 100

pointer) is thirty-five cents, the total price 245 of the weighed commodity is indicated by that figure in one of the rows 10 which is adjacent to the unit price "35" in the respective position of the pointer. The latter 5 may carry a wire 14 to facilitate the reading of the indications on the chart.

If commodities of a weight exceeding 10 pounds are to be placed on the platform, one 10 or more of the weights 15 may be placed on the attachment 5. The weight indications in the top row 9 will then have to be augmented by the value of that weight which has been placed on the attachment. The 15 total price of the commodity of this augmented weight, however, would not be ascertainable from the indicating chart itself.

The supplementary indicating device comprises a chart 20 with indications arranged 20 in horizontal rows 21 which can be placed in circumferential alignment with the arcuate rows 10 of the indicating chart; the indicator in the chart 20 are the values of fixed multiples of units, arranged in a way 25 similar to that which is provided on the main chart 7 and on the pointer 8.

Fig. 5 illustrates a supplementary chart of this character in which the second row 22 from the top shows the multiples of the 30 weight units, while the values of the total prices of these weight multiples for different unit prices are arranged in vertical groups in alignment with the respective weight multiples.

35 So, for instance, the vertical group of values indicated under the weight multiple of 30 pounds gives the price of 30 pounds of commodities, the unit prices of which are in the same relation to each other as the unit price indications on the pointer. If, therefore, in a weighing operation, for instance, upon placing an additional weight of 30 pounds on the attachment 5 the pointer should stop in alignment with the weight 40 indication 5, showing that 35 pounds is the correct weight of the load on the platform of the scale, the price indication on the chart 7 would be seventy-five cents at a unit price of 15 for the commodity. On the computing chart 20 the value "450" would appear 45 in the vertical group below the weight multiple "30" and in circumferential alignment with that row 10 of chart 7 which is underneath the unit price mark "15" of the pointer. The price indication of "75" on the chart 7 would then have to be added to the price indication "450" on the supplementary chart 20 thereby facilitating the computation of the prices in accordance 50 with the increased capacity of the scale.

To facilitate the exact reading of the supplementary chart 20, the latter is supported on a carrier 30 which is movably arranged with respect to the chart 7 so as to display 55 upon its adjustment only that portion of the

chart which corresponds to the increase of the weight capacity of the scale. The carrier 30 is constructed as a cylindrical member on the surface of which the supplementary chart is secured. This cylindrical carrier is supported in the casing extension 6 of the scale with its axis radially disposed to the same point towards which the groups of main indications on the permanent chart converge; and it is rotatably supported by 70 means of a bracket 31 near the upper end of the extension 6. A similar bracket 32 is attached to the extension at the lower end. The closing caps 33 of the cylinder are provided with axial posts or rods 34 which are rotatably mounted in the brackets 31, 32. A knurled button 35, secured to the upper rod, facilitates the rotary adjustment of the carrier. This carrier is arranged with respect to the display opening 16 in the extension of the scale so as to present one vertical group only of its values to the operator.

If, therefore, for instance a supplementary weight of 30 is placed on the attachment 5 the operator will turn the knob 35 until that vertical group of values below the multiple 30 is visible adjacent the permanent chart. It will be noted that one vertical column of the supplementary chart 20 is blank, the chart being adjusted to render this blank column visible to the operator when the article to be weighed does not exceed the weight of 10 pounds.

A second horizontal row 38 also indicating weight multiples of similar value as in row 22, but arranged in a different sequence, will upon rotation of the carrier 30 project the same weight multiple toward the customer or purchaser which in row 22 is displayed towards the operator, to indicate to the purchaser that the supplementary chart has been adjusted to the proper position with respect to the weight on the attachment.

The invention also comprises the arrangement of a yielding locking device to prevent accidental displacement of the chart and its carrier from adjusted position. The upper axial rod is provided with a ratchet or gear 39 having rounded teeth. In co-operation with this ratchet, a spring pawl 40 is secured to the casing of the scale adapted to engage the ratchet and yieldingly hold the same and thereby also the supplementary chart in adjusted position until the operator turns the knob, overcoming thereby the resistance of the spring dog 40. Any other suitable arrangement may be selected for retaining the parts in adjusted position.

In the operation of the scale the operator places the article on the platform and finds either through testing, whether the weight exceeds a certain multiple of tens of pounds, or he may add the weights in

accordance with his experience. After he increases for instance the weighing capacity of the scale by the addition of a weight of 40 pounds he turns the cylindrical carrier of the supplementary chart until the group of values below "40" is projected towards him. At the same time the value of "40" in the second row 38 will be turned towards the purchaser on the opposite side. If then the pointer should be arrested by the weight indication "5" of the permanent chart this will mean that the weight of the article on the platform is 45 pounds. If the unit price of the article is six cents the operator will read the value 30 which appears adjacent the unit price "6" of the pointer and to this he will add the value "240" of the supplementary chart in that row which is in circumferential alignment with the row underneath the unit price "6" of the pointer. In this way the computation of a very large number of multiples is readily ascertained on the scale and mistakes are avoided.

I claim:

25 1. A computing scale including a chart with total price graduations arranged in rows across it, a weight operated pointer

having price per unit graduations on it to cooperate with the graduations on the chart, and a second chart having rows of total 30 price graduations in multiples of those on the first mentioned chart, and brackets to support the second chart in a rotatable position parallel to the pointer when in its zero position, said brackets also supporting 35 the second chart in a position where the figures on the second chart will be in line with either corresponding rows of figures on the first chart.

2. In a computing scale, having a computing chart with total price indications arranged in rows, the values of said total price indications increasing from one end of the chart through the different rows to the other end of the chart, and a supplementary chart having multiple weight indications and total price indications for different unit prices in alinement with said multiple weight indications.

In witness whereof I have hereunto affixed my signature this 10th day of February, 1922.

ERNEST A. STEPHENS.
